UNITED STATES PATENT OFFICE.

MAXIMILIAN CHARLES SCHWEINERT, OF NEW YORK, N. Y.

ATTACHMENT FOR VALVE INSIDES.

Application filed May 20, 1922. Serial No. 562,503.

To all whom it may concern:

Be it known that I, MAXIMILIAN CHARLES SCHWEINERT, a citizen of the United States of America, residing in the borough of Manhattan, city, county, and State of New York, have invented certain new and useful Improvements in Attachments for Valve Insides, of which the following is a specification.

10 This invention relates to valves for pneumatic tires or the like, and particularly to the working parts or so-called valve insides, and more specifically to an attachment useful in connection with the same.
15 In certain types of valve insides the parts are so constructed that when the insides are separated from the valve casing (as well as when they are in place) the valve proper is urged against its seat by a spring. In any 20 type of inside it is detrimental for the valve proper to remain in contact with its seat up to the time of actual use within the valve casing, when, of course, such contact is essential. In the type referred to, however, 25 the valve proper not only contacts with its seat, but is urged against it with considerable force by its spring, and this condition prevails from the time of manufacture up to the time that the consumer finally places 30 the device in use. The rubber packing of the valve proper is by this means scored or indented, so that it is apt to be leaky when it is finally used. Some difficulty, although 35 to a much less degree, is experienced in the use of the standard valve insides, wherein the spring does not function to press the valve proper against its seat until the device is placed into use, but nevertheless, the mere 40 contact is detrimental, since it may result in a slight curing of the parts together, or a slight indentation, which will interfere with the tightness of the valve when it finally reaches the tire.

According to the present invention I provide a simple and effective means for avoiding this contact between the parts, which is applicable to the inside itself as distinguished from a container for the valve insides, or the valve casing itself.

50 In practically all types of valve inside there is provided a screw-threaded portion at the top, by means of which the valve inside is screwed into the valve casing, and there is also provided a pin which projects 55 beyond the screw-threaded portion designed eventually to become the deflating means

when the insides are in position in the casing. My present invention comprises an attachment adapted to be directly applied to the valve insides, and which preferably, although not essentially, utilizes such thread as a means for connection to maintain said valve proper in a position wherein it is disengaged from said seat. This attachment pushes down the pin, and thereby moves the valve proper from its seat and prevents its contact with the seat until the valve inside is ready for insertion in the casing. The means best adapted for the purpose is a simple cap threaded on its interior to engage the aforesaid thread of the inside.

In the drawings, wherein I have illustrated one form of the invention,—

Figure 1 is an elevation of a valve inside, showing the improved attachment connected thereto.

Fig. 2 is an enlarged view of Fig. 1, most of the parts being shown in diametrical section.

Fig. 3 is a view of the top of a valve casing, showing the inside in position.

Fig. 4 is a cross-section on the line 4—4 in Fig. 2.

Referring to the drawings which illustrate one form of the invention, let A indicate the insides as a whole. In the type illustrated the insides comprise a shell B, having an exterior thread C designed to screw into the valve casing, a seat D at the bottom adapted to make contact with the valve proper E and a packing washer F adapted to make a tight joint with the usual tapered seat G formed on the valve casing H. Above the seat G and located in a suitable bore is a spring J, the lower end of which presses against the bottom of the bore and the upper end of which engages a collar K formed or carried by the valve pin L to which the valve proper E is connected. This construction of valve inside is already known and is used for an illustration of a type in which there is constant pressure of the valve proper E against the seat D, irrespective of whether or not the device is in position in the casing. The present device is, however, applicable to other forms than that shown, although it is of special utility in connection with the type illustrated.

According to the present invention, I provide a means for engaging the valve inside and also the pin L, whereby to displace the pin downwardly, thereby moving the valve

proper E from its seat. While this may be accomplished in various ways, the preferred form is that shown wherein I provide a simple cap M, having an internal thread 5 adapted to engage the external thread C of the valve insides, and by application to the latter, move the pin L sufficiently inward to take the pressure from the spring J and hold the valve proper off its seat. Usually 10 the pin extends far enough beyond the end of the shell of the valve insides to be engaged by the cap M without the latter projecting into the valve inside. However, if the pin is shorter, the cap M may be provided with a depression or the like which 15 will insure sufficient contact to accomplish the purposes mentioned.

The cap M may be variously formed, and 20 there may be substituted for it any means for engaging the shell of the valve inside and the pin L to hold the latter depressed.

The device is also useful in connection 25 with the standard inside to insure that the valve proper does not contact with its seat before being placed into use.

It will, of course, be understood that the 30 cap or its equivalent should be applied to the valve inside as soon as the latter is manufactured, and remain in position until the consumer desires to apply it to the valve casting, whereupon the attachment is removed and thrown away if desired. The cap may be very cheaply constructed of thin sheet metal with a rolled thread.

35 While I have shown and described one

form of the invention, it will be understood that I do not wish to be limited thereto, since various changes may be made therein without departing from the spirit of the invention.

40

What I claim is:—

1. The combination with a valve inside having a seat and a valve proper, of means carried by the valve inside for holding the valve proper in a position in which it is disengaged from its seat.

45

2. The combination with a valve inside having a seat and a valve proper, of means carried by the valve inside for holding the valve proper in a position in which it is disengaged from its seat, said means comprising a device engaging a screw-thread on the valve inside.

50

3. The combination with a valve inside having a seat and a valve proper, of means carried by the valve inside for holding the valve proper in a position in which it is disengaged from its seat, said means comprising a screw-threaded cap engaging a screw-thread on the valve inside.

55

4. The combination with a valve inside having a seat and a valve proper, a spring carried by said inside, a pin connected with the valve proper against which said spring acts, and a member engaging the valve inside and said pin.

60

In witness whereof, I have hereunto signed my name.

MAXIMILIAN CHARLES SCHWEINERT.
